HEATING BOILER WITH HEATING SURFACE
REDUCED BY IMPROVED CONVECTION

John Anders Rydberg, Stockholm, Sweden, assignor to Aktiebolaget Gustavsbergs Fabriker, Gustavsberg, Sweden, a corporation of Sweden

Application February 1, 1949, Serial No. 73,888
In Sweden January 30, 1948

6 Claims. (Cl. 122—120)

1

This invention relates to a heating boiler, in which by special construction an improved convection is obtained, while at the same time the heating surface required is reduced. This invention is related to that disclosed in application Serial No. 73,890, filed February 1, 1949.

Heating boilers of the type referred to consist of a combustion chamber and a flue gas system connected with same, in which water-filled partitions connected with the water space of the heating boiler conduct the flue gases in zigzag paths, before they emerge through the flue gas discharge, usually a chimney.

The draft required for a heating boiler is usually generated by means of a chimney. In certain cases, however, it has been suggested that the draft should be improved by means of a fan. Such a fan has also been used for overcoming excessive resistance in the grate or fuel layer. Any increase in the flow rate of the flue gas current in the boiler flues was not desired beyond the normal gas flow rate resulting from a good chimney and other satisfactory draft conditions, which rate can be stated to be less than $W=1.5N/m^2.s.$ where W is the gas flow rate in cubic meters per square meter of gas channel flow section per second and the normal gas volume N is expressed as m^3 gas at $0^\circ C.$ and 760 mm. Hg (normal cubic meters).

In heating boilers with a fan it has been found to be economically advantageous to increase the gas flow rate in the flues above the hitherto usual flow rate. At an increasing gas flow rate it will be found that the heat transfer coefficient of the heating surface increases, and thus the size of heating surface required for a certain purpose decreases. The dimensions and space required for the heating boiler can thus be reduced.

It can be proved, however, that if the gas flow rate increases above a certain limit, the cost of power for the fan will increase faster than the cost of the heating surface decreases. This invention is based on the knowledge that a higher gas flow rate is suitable and that such a rate can be determined as the most economical, i. e. a rate, at which the total of operating cost for generating the draft and of the annual amortization for the heating surface required can be determined as a minimum.

The pressure drop P in the heating boiler flues can be expressed by formula:

$$(1) \quad P = A \cdot w^n$$

The heat transfer coefficient k for the convection heating surface is approximately:

2

$$(2) \quad k = B \cdot W^u$$

In these expressions, A , B , n and u are constants, and W = the gas flow rate in the boiler flues in N . The formula for obtaining the pressure drop P given above is based on the fact that such pressure drop is dependent on the gas flow rate W in the flues. Experiments have shown that P is proportional to an exponential function of the gas flow rate W as expressed by the formula where n is the exponential value by which P depends on W and in which A is a factor of proportionality. As in the formula for k the terms A , B , n and u are numerical values. Those for n and u have been found by experimentation to be 1.8 and 0.8 respectively, and for B to be

$$3.8 \\ d^{0.25}$$

20 where d is the hydraulic diameter of the flue.

The total cost of the power for the fan and of the annual amortization for the convection heating surface can be expressed thus:

$$25 (3) \quad K = P \cdot G \cdot r \cdot Z + E \cdot a$$

where

G = gas volume per time unit

r = cost of power

30 E = convection heating surface area

a = annual amortization per m^2 heating surface

Z = operating time per year.

For cooling down in the boiler flues there is 35 the following relation:

$$40 (4) \quad \log_e \frac{t_1 - t_2}{t_2 - t_3} \cdot \frac{k \cdot E}{G \cdot C_p}$$

where

t_1 = temperature of flue gases before contact with the convection heating surface

t_2 = temperature of flue gases upon leaving the convection heating surface

45 t_3 = temperature of heating surface

C_p = specific heat of flue gases.

If it is desired to cool down the flue gases to a certain value, independently of variations in gas flow rate and in heating surface, this can be expressed by:

$$50 (5) \quad \frac{k \cdot E}{G} = C$$

55 where C is a constant.

The above expression for the cost K may now be written by substituting (1), (2) and (5) in (3):

$$(6) \quad K = A.W^n.G.r.Z + \frac{C.G}{B.W^u} \cdot a$$

If cost K is derived with regard to gas flow rate W for a constant value of the gas volume per time unit, the following is obtained:

$$(7) \quad \frac{dK}{dW} = Z.A.r.GnW^{n-1} - \frac{C.a.G.u}{B} \cdot \frac{1}{W^{u+1}}$$

The value of gas flow rate W, which gives a minimum for cost K, is obtained by putting down 0 (zero) for this derivative. Thus the following expression is obtained for the economical value of W:

$$(8) \quad W_e = \left[\frac{C.a.u}{A.B.r.n.Z} \right]^{\frac{1}{u+1}}$$

My investigations have shown that one can put, with sufficient safety, 2.6 for $u+1$.

This shows that the variation in boiler amortization and power prices, a and r respectively, and the operation time Z has no considerable effect upon the economical gas flow rate W_e . I have thus succeeded in establishing that there is an economical value of gas flow rate and that this value W_e will vary comparatively slightly in the case of variations in prices and method of operating. My investigations have further shown that W_e normally is in the neighborhood of $6N/m^2s$, and that this value has comparatively general validity. Around the economical value W_e for the gas flow rate, cost K is found to vary very slightly. Owing to my investigations I have found that from a practical and economical point of view it is sufficient, if the gas flow rate is kept within the limits (3 to 10) N/m^2s . As an example I show in Fig. 1 of the drawings a diagram of the relation between the cost

$$\frac{K}{G}$$

per year for cooling down the gas flow in N per operating hour and the gas flow rate W in N/m^2s in the flue system. The gas flow has been assumed to enter the convection surface at $1100^\circ C$. and to leave it cooled down to $200^\circ C$, and the number of operating days of 24 hours each per year of the heating boiler has been assumed to be 240, all values quite normal. The diagram shows that the cost per year has a minimum at a gas flow rate of $6N/m^2s$, and that the curve around this value is rather flat, which means that the gas flow rate W can be varied within the limits (3 to 10) N/m^2s . without considerably increasing the cost per year.

The invention thus relates to a heating boiler of the type previously described, with a fuel storage compartment and flue system and a fan arranged between the flue system and the flue gas discharge, for instance a chimney. According to this invention, the flue gas system is constructed as a convection surface with a high heat transfer figure by locating the flue gas flow rate within the limits (3 to 10) N/m^2s . by means of suitable selection of the capacity of the flue gas fan in relation to the heating surface of the boiler. This invention relates in particular to a heating boiler with a gas flow rate in the flue system of $6N/m^2s$. or in the neighbourhood of this figure. In the case of large heating boiler plants of, for instance, 1 million kilogram calories per hour for larger buildings or similar pur-

poses, the convection heating surface can be reduced to half the area with good economy. It is evident that by this a considerable saving in space and cost is attained. Moreover, it has become possible, owing to this invention, to exceed the upper limit for heat production in one single boiler unit, which in practice formerly had been fixed with regard to the possibility that they might be placed in, for instance, a block of buildings.

As distinguished from other known heating devices with increased flue gas flow rate, the water spaces of the flues of the present boiler are constructed as plane water walls.

The construction of the heating boiler proposed may be varied in other respects than those already mentioned, by making use of known principles for heating boilers, in particular the construction of large ones. Attention is, however, called to a special design where a secondary combustion or flame chamber is arranged between the fuel storage compartment and the flue system.

A heating boiler constructed according to this invention is shown as an example in Figs. 2-4 of enclosed drawings. Fig. 1 is a diagram showing the relation between the cost K/G per year for cooling down the gas flow in cubic meters per operating hour and the gas flow rate W in meters per second, Fig. 2 is a longitudinal section of the heating boiler, Fig. 3 is a sectional view on the line 3-3 of Fig. 2, and Fig. 4 is an elevational view of the boiler seen from the rear.

Referring to Fig. 2, the heating boiler shown has a fuel compartment 4 forming a shaft for the fuel, which is put in from the top of the boiler. The lower portion 4' of compartment 4 provides a primary combustion chamber. The fuel compartment is closed as shown in Figs. 2 and 4 by means of a removable cover 14 of the following construction. The cover 14 fits tight with a groove 13 against the upper edge 9 of the fuel compartment and can by means of a lever mechanism 12, 21 and bar 14' be lifted to a position, where by means of suitable mechanical devices it will rest on two pairs of wheels 11, 22, which in turn are so arranged that cover 14 when lifted is moved to one side on rails consisting of Z-shaped beams 10, 23 on the boiler top. The top of the fuel storage compartment will thus be open for filling it with large size fuel such as wood. The removable cover 14 in turn has an opening 15 closed by a smaller lid 16, attached by means of a bayonet catch 19 and intended for putting in less bulky fuel, such as for instance coal, etc. The bar 14' is attached to the lid 16. The cover unit is fitted with protective plates 18, 24 on the side exposed to the fuel compartment as shown in Fig. 2 and with insulation 17 and 20 of glass wool, asbestos or similar material put in between.

Certain of the walls of the fuel compartment and primary combustion chamber are constructed as plane, flat water spaces 5, 26, 31, 85, 85. The water spaces in the two walls in longitudinal direction of the boiler, 85, 85, are enlarged to form longitudinal chambers 6, 6, below the boiler top. The return water enters one of these chambers through a connection 7. Water space 5 at the front of the boiler communicates by means of a connection 8 with the hot water line fed by the boiler. On the boiler front there are two pairs of furnace doors 2, 3—one pair 3 above and the other pair 2 below a removable grate 1 in the lower part of the fuel shaft. Grate 1 consists of

tubes attached between the front and rear water spaces 5 and 31 respectively of the fuel compartment and primary combustion chamber. Water flows through the grate tubes 1 so that the grate is water-cooled. In the wall 26, 31 of the fuel compartment and primary combustion chamber there is a flue gas opening, 30, through which the flue gases pass to subsequent sections of the boiler. Disposed within the fuel storage compartment is a fuel bridge 27, slanting downwardly from a point at the rear of the fuel shaft and terminating at a suitable height above the grate 1, for instance a little above the level of the upper edge of flue gas opening 30. Said fuel bridge 27 consists of a water-filled wall communicating with the other water spaces of the boiler by means of connections 25, 28. The purpose of fuel bridge 27 is to provide a larger separating area 29 at the gas discharge opening 30 in the lower part of the fuel storage compartment, where the flue gases are discharged. Thus the resistance at the gas discharge opening 30 from the fuel storage compartment is reduced owing to lower gas flow rate in said separating area 29. This is advantageous when small size fuel is used, such as coal, coke, sawdust, or similar material. The boiler also becomes less sensitive to accumulation of ash and slag at the flue gas opening 30, which might cause considerable resistance.

The flue gases leaving through gas discharge 30 are conveyed to a secondary combustion or flame chamber 41 while being mixed with secondary air entering through a secondary air inlet 32. In this inlet 32 a damper 33 is arranged for regulating the quantity of incoming secondary air. In the secondary combustion chamber 41 a thermostat 42 can be arranged, which operates the damper 33. Said secondary combustion chamber 41 is arranged between the rear vertical water space 26 of the fuel storage compartment and a subsequent, likewise vertical water space 40, which water spaces communicate with the longitudinal water spaces 85, 85 of the boiler. That part 31 of the rear wall of the fuel compartment, which lies below flue gas discharge 30, is water-filled and bent first rearwardly and then upwardly for directing the flue gases into the secondary combustion chamber 41. This part 31 of the wall forms together with the vertical water space 40 the limiting surfaces of the secondary air intake 32. The flue gases are forced to flow upwardly to the secondary combustion chamber 41 through a substantially S-shaped conduit 37, formed by horizontal ledges 36 and 38, projecting into the secondary combustion chamber 41 from walls 26 and 40 respectively. These ledges 36 and 38 are also water-filled and are intended for mixing the flue gases with incoming secondary air. It has proved very difficult to mix the flue gases and the secondary air. The secondary air intake 32 enters in the lower part of the S-shaped mixing conduit 37 through a number of oblique slits 34, parallel with the longitudinal direction of the boiler, in order to divide the secondary air into a number of parallel air currents. The flue gas and secondary air currents by this device are forced to thoroughly mix with each other, and mixing is completed at the points of change in direction, which follow immediately, as stated above. By these changes in direction a violent whirling motion of the gas mixture is obtained, so that complete combustion results with a minimum surplus of air.

If desired the limiting edges surrounding the

secondary air inlet slits 34 may extend upwardly in the shape of guide sleeves so that these sleeves terminate approximately at the level of the lower edge of the lower horizontal ledge 36. This will also divide the flue gas flow into a plurality of paths which facilitate the efficient mixing with secondary air.

The temperature in the secondary combustion chamber 41 varies with the load and surplus of air in such a way that the heavier the load, the higher the temperature in the secondary combustion chamber. Further, the larger the surplus of air, the lower the temperature in the secondary combustion chamber at the same load. The demand for secondary air is larger at heavy loads than at light loads and it is smaller at a large surplus of air than at a smaller one. By placing in the secondary combustion chamber 41 the thermostat 42 the supply of secondary air may be controlled by means of damper 33 operated by the thermostat depending upon whether the temperature of the secondary combustion chamber drops or rises. In the case of hollow spaces in the fire, for instance, a considerable surplus of primary air and a low temperature in the combustion chamber is obtained, which is accompanied by a decrease in secondary air supply. If a slide occurs in the fire, there will be a sudden increase in combustion intensity with a great demand for secondary air. The temperature in the secondary combustion chamber rises, while the supply of secondary air increases at the same time.

From the secondary combustion chamber 41 the flue gases enter the convection zone of the heating boiler. This zone is formed by a number of hollow, relatively flat, water-filled, vertical partitions 40, 49, 80, 56 and 77, which alternately project upwardly from the bottom of the boiler and downwardly from the top of the boiler, so that the flue gases flow through the vertical passages, 84, 81, 74, 76, thus formed in zigzag paths before leaving the boiler through the smoke gas exit 73. The flue gases enter the convection zone through opening 44, which is formed at the top in the rear part of the secondary combustion chamber by the rear water-filled wall 40 terminating below the boiler top. The sides of passages 84, 81, 74 and 76 facing each other are fitted with vertical flanges or fins 63, which are situated opposite each other in pairs and almost meet, and which divide the flue gas current into parallel partial currents.

An important detail for rendering possible high economical gas flow rates is that the boiler flues 84, 81, 74, 76 are shaped as diffusers 83, 53, 78, 61 in connection with every change in direction, i. e. when changing from downwardly to upwardly direction and vice versa, so that the gas flow rate is reduced before the direction is changed. This has been attained by making the ends 83, 53, 78, 61 of partitions 40, 49, 80, 56, 77 tapering at the bends 82, 52, 79, 60 of the flue gas system so that the flue gas passages expand. This reduces the pressure losses in the flue bends 82, 52, 79, 60 to acceptable values. Without this arrangement, the combined pressure drops in the bends would dominate, which is not desirable, as it is only pressure drops due to friction along the heating surface that efficiently contribute to an improvement of heat transfer.

Partitions 40, 49, 80, 56, 77 communicate with the longitudinal water spaces 85, 85 of the heating boiler. Between a horizontal ledge of wall part 26 and partition 49 there is a soot opening

43 at the top, which is closed by a removable cover 46. Soot hole covers 50 and 57 also close openings 51 and 58 arranged on the boiler top between partitions 49 and 56, and between 56 and 17 respectively. Of these soot hole covers, the former, 46 and 50, are fitted with a protective plate underneath, 48 and 55 respectively, and with insulation inserted between these plates and upper plates 47 and 54 respectively, for instance glass wool, whereas the last soot hole cover 57 is of simpler construction and without insulation. On top of the secondary combustion chamber and the convection chambers as shown in Fig. 2 a removable cover plate 45 is placed on suitable supports of sectional iron. Secondary air is assumed to enter through opening 59 left by the cover plate 45 at the rear upper end of the convection system, flowing along the space under the cover plate and entering vertical passages 39 at the sides of the secondary combustion chamber 41 and finally entering, duly preheated, the secondary combustion chamber 41 through secondary air intake 32.

The flue gases are discharged at the top from the last gas passage 62 of the boiler, entering a vertical flue gas discharge passage 62, which is connected with a flue gas fan 68, as shown in Fig. 2, by means of a central outlet 66 and with the chimney by means of a smoke gas discharge 13 at the bottom. Fan 68 is in turn also connected with said smoke gas discharge 13. In the smoke gas discharge flue 62 two dampers are arranged: one, 64, upstream of the fan outlet 66, and another one, 75, downstream of the same. The former damper 64 is kept open sufficiently for regulating the discharge of flue gas, while the latter, 75, is kept closed in order to prevent closed circulation of the gas volume under the upper damper 64 through fan 68. On fan casing 67 there is arranged a supporting structure 69 for the motor 70, which by means of a belt 71 drives shaft 72 of the impeller.

The longitudinal sides and the rear of the heating boiler are covered with a layer of insulating material 65.

The heating boiler shown is constructed with regard to such a design of the heating surface and adaption of the fan so that the above explained advantageous gas flow rate in the convection system of (3 to 10) N/m^2s , in particular $6N/m^2s$. or a figure in that neighbourhood, is obtained.

What I claim is:

1. A water heating boiler of the water wall type having a combustion chamber, flue gas passages of substantially rectangular cross-section in said boiler defined by water filled parallel and substantially vertical partitions, fins on said partitions disposed in said passages, said partitions alternately terminating in spaced relation to the upper and lower internal walls of said boiler thus providing an elongated serpentine path for said gases, a flue gas outlet and a circulating fan disposed between said passages and said outlet, the capacity of said fan and the cross sectional area and arrangement of said passages being so coordinated that the rate of flow of said gases within said passages is within the limits (3 to 10) N/m^2s . and the heat transfer coefficient is substantially equal to $BW^{0.8}$ and in which

N =normal gas volume in cubic meters at 0° and 760 mm. Hg
 m^2 =Cross section of flue in square meters
 s =seconds
 $B=3.8d^{-25}$

d =hydraulic diameter of the flue and
 W =gas velocity in meters/sec.

2. A water heating boiler of the water wall type having a combustion chamber, flue gas passages in said boiler defined by water filled parallel and substantially vertical partitions, said partitions alternately terminating in spaced relation to the upper and lower internal walls of said boiler thus providing an elongated serpentine path for said gases, a flue gas outlet and means disposed between said passages and said outlet for forcibly circulating said gases, the capacity of said means and the cross sectional area and arrangement of said passages being so coordinated that the rate of flow of said gases is within the limits (3 to 10) N/m^2s . and the heat transfer coefficient is substantially equal to $BW^{0.8}$ and in which

20 N =normal gas volume in cubic meters at 0° and 760 mm. Hg
 m^2 =Cross section of flue in square meters
 s =seconds
 $B=3.8d^{-25}$

25 d =hydraulic diameter of the flue and
 W =gas velocity in meters/sec.

3. A heating boiler as defined in claim 1 in which the rate of flow of said gases is approximately $6N/m^2s$.

30 4. A heating boiler as defined in claim 1 in which a second combustion chamber is disposed between the primary combustion chamber and said flue gas passages.

5. A water heating boiler of the water wall type 35 having a combustion chamber, flue gas passages in said boiler defined by water filled parallel and substantially vertical partitions, said partitions alternately terminating in spaced relation to the upper and lower internal walls of said boiler thus providing an elongated serpentine path for said gases, a flue gas outlet and a circulating fan disposed between said passages and said outlet, the capacity of said fan and the cross sectional area and arrangement of said passages being so coordinated that the rate of flow of said gases within said passage is within the limits (3 to 10) N/m^2s . and the heat transfer coefficient is substantially equal to $BW^{0.8}$ and in which

45 N =normal gas volume in cubic meters at 0° and 760 mm. Hg

50 m^2 =Cross section of flue in square meters

s =seconds

$B=3.8d^{-25}$

55 d =hydraulic diameter of the flue and

W =gas velocity in meters/sec.

6. A water heating boiler of the water wall type having a combustion chamber, flue gas passages in said boiler defined by water filled parallel and substantially vertical partitions, said partitions alternately terminating in spaced relation to the upper and lower internal walls of said boiler thus providing an elongated serpentine path for said gases, opposed vertical fins on said partitions providing separate gas flow paths, a flue gas outlet and a circulating fan disposed between said passages and said outlet, the capacity of said fan and the cross sectional area and arrangement of said passages being so coordinated that the rate of flow of said gases within said passages is within the limits (3 to 10) N/m^2s . and the heat transfer coefficient is substantially equal to $BW^{0.8}$ and in which

70 N =normal gas volume in cubic meters at 0° and 760 mm. Hg

75 m^2 =Cross section of flue in square meters

s =seconds

$B=3.8d^{-25}$

m^2 =Cross section of flue in square meters
 s.=seconds
 $B=3.8d^{-25}$
 d =hydraulic diameter of the flue and
 W =gas velocity in meters/sec.
